US0D1056930S

(12) **United States Design Patent** (10) Patent No.: **US D1,056,930 S**
Jeong et al. (45) Date of Patent: ** Jan. 7, 2025

(54) **DISPLAY SCREEN OR PORTION THEREOF WITH GRAPHICAL USER INTERFACE**

(71) Applicant: **Samsung Electronics Co., Ltd.**, Gyeonggi-do (KR)

(72) Inventors: **Sunghyo Jeong**, Gyeonggi-do (KR); **Minji Cho**, Gyeonggi-do (KR)

(73) Assignee: **SAMSUNG ELECTRONICS CO., LTD.**, Gyeonggi-Do (KR)

(**) Term: **15 Years**

(21) Appl. No.: **29/870,472**

(22) Filed: **Jan. 27, 2023**

(30) **Foreign Application Priority Data**

Aug. 5, 2022 (KR) 30-2022-0031818
 Aug. 5, 2022 (KR) 30-2022-0031819

(51) **LOC (15) Cl.** **14-04**

(52) **U.S. Cl.**

USPC **D14/486**

(58) **Field of Classification Search**

USPC D14/485-495

See application file for complete search history.

(57) **CLAIM**

The ornamental design for a display screen or portion thereof with graphical user interface, as shown and described.

DESCRIPTION

The FIGURE is a front view of a display screen or portion thereof with graphical user interface, showing our new design.

The outer perimeter broken lines in the FIGURE depict a display screen or portion thereof and form no part of the claimed design. The remaining broken lines in the FIGURE depict portions of the graphical user interface that form no part of the claimed design.

1 Claim, 1 Drawing Sheet
